UNITED STATES PATENT OFFICE.

HOWARD PAUL CULVER, OF ASHLAND, WISCONSIN.

DESIGN FOR A GAS-ENGINE BODY.

48,774.

Specification for Design.

Patented Mar. 28, 1916.

Application filed December 17, 1915. Serial No. 67,474. Term of patent 3½ years.

To all whom it may concern:

Be it known that I, HOWARD PAUL CULVER, a citizen of the United States, residing at Ashland, in the county of Ashland and State of Wisconsin, have invented a new, original, and ornamental Design for a Gas-Engine Body, of which the following is a specification, reference being had to the accompanying drawing, forming a part thereof.

In the drawing: Figure 1 is a side view and, Fig. 2 is an end view of a gas-engine body showing my new design.

I claim:

The ornamental design for a gas engine body, as shown.

H. PAUL CULVER.

Witnesses:

LEME M. LEFEBORE,
MARGARET F. KELLY.
